UNITED STATES PATENT OFFICE.

PERLEY LAFLIN, OF WARREN, MASSACHUSETTS, ASSIGNOR TO HIMSELF
AND JOHN J. SPRAGUE.

IMPROVEMENT IN SHUTTLES.

Specification forming part of Letters Patent No. 79,483, dated June 30, 1868.

To all whom it may concern:

Be it known that I, PERLEY LAFLIN, of Warren, in the county of Worcester and Commonwealth of Massachusetts, have invented certain new and useful Improvements in Shuttles; and I do hereby declare that the following is a full, clear, and exact description of the same, reference being had to the accompanying drawings, forming a part of this specification, in which—

Figure 1 represents a perspective view of a power loom-shuttle with my improvements applied thereto; and Fig. 2 represents a section on line A B, Fig. 1.

To enable those skilled in the art to which my invention belongs to make and use the same, I will proceed to describe it more in detail.

My present improvements have reference to certain devices for facilitating the threading of shuttles, my object being not only to allow the thread to be quickly and readily passed through the quill or tube in the shuttle, but to remove, as far as possible, all liability of its pulling out after being inserted. These results I have obtained by the employment of the device which will now be described.

In the drawings, a shuttle, A, is shown, with a bobbin, B, upon its spindle, the thread *a* being passed or drawn through the hole or tube *b*. A slot, *e*, is cut down through the side *C* of the shuttle into the hole *b*; but this slot of itself would not answer the purpose I have in view, since the yarn could not be slipped in conveniently or quick enough, while even if once in place it would be liable to pull out.

I therefore insert a metal guide-piece, *d*, in the hole and slot, having a flattened inwardly-projecting lip, *e*, which extends in toward the middle of the shuttle, as shown in the drawings. The upper edge of the shuttle is cut out to let the outer edge of lip *d* down flush with the top of the shuttle, where it is securely held by a pin, 1. Lip *e* is rounded off upon the edge 2 next to the bobbin, so that a point, 3, is left, over which the operator slips the thread, which is then quickly drawn down over the inclined part 4 of the guide-piece *d* into the tubular part *b*, as shown in the drawings. The projecting lip *e* not only facilitates the threading of the shuttle, but at the same time prevents the thread from flying out during the operation of weaving. Owing to the peculiar manner of fitting in the guide-piece *d*, in combination with the fastening-pin 1 and shoulder 5 on the shuttle-wood, it is not liable to become loosened by its use in the loom.

With a little practice the operator can thread one of my improved shuttles much quicker than by the old practice of "sucking" the thread through the tube.

Having described my improved shuttle, what I claim therein as new and of my invention, and desire to secure by Letters Patent, is—

The combination, with the shuttle, of a threading and guide piece or lip, constructed as described, and for the purposes set forth.

PERLEY LAFLIN.
